CLAIM

The ornamental design for a trigger guard for firearm as shown and described.

DESCRIPTION

FIG. 1 is a perspective view of a trigger guard for firearm showing the new design;

FIG. 2 is a perspective view thereof;

FIG. 3 is a perspective view thereof;

FIG. 4 is a perspective view thereof;

FIG. 5 is a left side view thereof;

FIG. 6 is a right side view thereof;

FIG. 7 is a top view thereof;

FIG. 8 is a bottom view thereof;

FIG. 9 is a front view thereof; and,

FIG. 10 is a rear view thereof.

The broken lines are included for the purpose of illustrating features that form no part of the claimed design.

1 Claim, 5 Drawing Sheets
